UNITED STATES PATENT OFFICE.

HARRIET A. SCHANDEVYL, OF EAST SAUGUS, MASSACHUSETTS.

IMPROVEMENT IN COMBINED SKIRT-SUPPORTERS AND CORSETS.

Specification forming part of Letters Patent No. 178,333, dated June 6, 1876; application filed April 24, 1876.

To all whom it may concern:

Be it known that I, HARRIET A. SCHANDEVYL, of East Saugus, of the county of Essex and State of Massachusetts, have invented a new and useful Combined Skirt and Bust Supporter; and do hereby declare the same to be fully described in the following specification, and represented in the accompanying drawing, which is a side view of it.

The object of the article hereinafter described is to support, at one and the same time, the breasts and skirt or drawers of a woman, and for such purpose the suspenders constituting part of the said article are extended both above and below the gored breast-sustaining sections, all as hereinafter explained.

In such drawings, A A denote a pair of shoulder straps or suspenders, provided with auxiliary fore straps a a, and connected by elastic dorsal straps b c c, arranged as shown. To these suspenders there are fastened the two sections or parts B B of a waist or bust supporter, the said sections being provided with gores or pockets, as shown at C C, for receiving and supporting the breasts of a woman while wearing the article. One of the sections B B has a series of buttons, d, and the other a corresponding series of button-holes, e, arranged with it, as shown, and each

section is also provided with a strap, f, extending from it, as represented. The suspenders are to sustain a skirt or drawers and the bust-supporter, to which they are to be fastened by pins, buttons, or other proper devices. The additional straps f f also serve, with the bust-supporter, to support a skirt or the drawers of the wearer. The suspenders are to cross the shoulders of the person and be buttoned or pinned to the upper portions of the bust-supporter.

The article is one which, when in wear, affords much comfort to a person, as it not only advantageously supports the breasts, but prevents the skirt or skirts or drawers from bearing down upon the hips and abdomen.

I claim as my invention—

1. The combination of the skirt-suspenders A A, fore straps a a, and the gored bust-supporting sections B B, constructed and arranged substantially as set forth.
2. The combination of the skirt-suspenders A A, the fore straps a a, gored bust-supporting sections B B, and the auxiliary straps f f, all being arranged and applied substantially as specified and represented.

H. A. SCHANDEVYL.
